SHOTGUN MAGAZINE

John E. Russell, Glendale, Douglas B. Ellis, Webster Groves, and Robert E. Gardiner, Normandy, Mo., assignors to Browning Arms Company, St. Louis, Mo., a corporation of Utah

Application February 9, 1935, Serial No. 5,780

5 Claims. (Cl. 42—49)

This invention relates to shot gun magazines, and with regard to certain more specific features, to shot gun magazines of adjustable capacity.

Among the several objects of the invention may be noted the provision of means for reducing the cartridge capacity of the magazines of automatic or auto-loading or repeating shot guns, without interfering with any of the operating mechanisms of said magazine; the provision of means of the class described which may readily be inserted at will without the use of special tools, and may similarly be withdrawn, in order that the magazine may be altered in capacity as circumstances require with a minimum of trouble; the provision of means of the class described which is economical to manufacture and which may therefore be made at a low cost. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a side elevation of a shot gun, certain portions being broken away;

Fig. 2 is a longitudinal cross section of a magazine showing the present invention;

Fig. 3 is a view similar to Fig. 2, but showing the magazine in loaded condition; and,

Fig. 4 is a view similar to Figs. 2 and 3, but showing the magazine independent of the use of the present invention.

Similar reference characters indicate corresponding parts throughout the several views of the drawing.

Certain legal restrictions have recently been imposed upon the capacity, in cartridges of the magazines of automatic or auto-loading or repeating shot guns when they are used for particular purposes, such as shooting migratory birds. In general, these restrictions limit the total capacity of the gun to three cartridges, which means one in the firing chamber and two in the magazine.

It so happens that practically all of the magazine shot guns in use today, and those being manufactured, are equipped with magazines having a capacity considerably in excess of the limit of two imposed by the above regulations.

Permanent change of all of these shot guns would not only be an impossible task, because of their wide distribution in the hands of individual owners, but it would involve so serious a change in the design and balance of the guns as to 5 make it extremely impractical to achieve. Further, even if the permanent reduction of capacity could be made, it would not be desirable, as the capacity of the magazine is not restricted except in named fields and for non-restricted 10 fields the average user prefers to have a magazine of a four or five shot capacity. Thus, the ideal magazine is one which can only be limited in capacity to two cartridges when the gun is being used in the restricted field, but can be 15 permitted to receive a greater number of cartridges when the gun is being used in a non-restricted field.

The present invention provides just such a device, which is readily adaptable to existing 20 larger-capacity shot gun magazines, and which can be furnished to the purchaser of a new gun as an auxiliary.

Referring now more particularly to Fig. 1, numeral 1 indicates, in somewhat diagrammatic 25 form, the stock of an automatic shot gun. Numeral 2 indicates broadly the firing mechanism. Numeral 3 indicates the barrel. Numeral 4 indicates the magazine, and numeral 5 indicates the resilient entering means by which 30 cartridges are loaded into the magazine. So far as is apparent in Fig. 1, the gun is of a standard construction available on the market.

The repeating and firing mechanisms of the gun are of no consequence to the present in- 35 vention; hence they will not be described in detail.

The magazine 4 (referring more particularly to Figs. 2, 3 and 4) comprises a tube 6, which is threaded at one end to receive a cap 7, and 40 at the other end, as indicated by numeral 8, to thread into a suitable receiving means 9 (see Fig. 1) on the gun itself. Inside the tube 6 is slidably arranged a cup-shaped retainer cap 10, which, at its inner edge, is provided with an 45 outwardly extending flange 11. The tube 6 is provided with a shoulder 12 which cooperates with the flange 11 of the cap 10 to prevent it from being ejected from the end 8 of the tube. In assembly, the cap 10 is dropped into the opposite 50 end of tube 6, which receives the cap 7.

At the other end of the tube 4 is a press-fitted, cup-shaped retainer cap 13, which faces in the opposite direction from the cap 10. The circular 55

portion 14 of the cap 13 has a central circular opening 15 therein.

Between the caps 10 and 13 is supported a compression spring 16. Inasmuch as the cap 13 is pressed in position, it constitutes a relatively fixed abutment for the spring 16 and thus the cap 10 is normally resiliently maintained at the end 8 of the magazine tube, as shown in Fig. 2.

10 In the procedure of loading the magazine, as indicated in Fig. 1, cartridges 17 are advanced against the cap 10, compressing the spring 16 and causing the cap 10 to recede into the magazine tube. Lacking obstruction, in the particular tube illustrated, this compressing may be carried on until four cartridges 17 have been inserted in the tube, as shown in Fig. 4.

The description up to the present point has concerned the magazine as it has heretofore been made. The device for reducing the capacity of the magazine, which is novel with the present invention is the plug indicated generally by numeral 18 in Figs. 2 and 3. This plug 18 is preferably made of wood, such as 25 hickory (although it may well be made of metal or other material without altering its functional characteristics) and comprises a cylindrical shank 19 and a circular head 20. The length of the shank 19 is determined by the number 30 of cartridges by which it is desired to reduce the capacity of the magazine. In the present instance, the shank is roughly equivalent to the length of two cartridges, because it is desired to reduce the capacity of the magazine by two 35 cartridges. The head 20 of the plug 18 is desirably of considerable thickness, lengthwise of the plug, for reasons to be pointed out hereinafter. The diameter of the head 20 is such as will afford a sliding, albeit rather tight fit in 40 the tube 6.

The assembly of the plug 19 with the magazine is a simple matter, readily within the capability of the user of the gun in the field. For example, all that need be done is to remove 45 the cap 7 from the tube 6, press the cap 13 sufficiently far into the tube 6, if it is not already so, and insert the shank 19 of the plug 18 through the hole 15 in the cap 13. When the cap 7 is then threaded on to the tube 6, it clamps the plug 50 18 in position.

The thickness of the head 20 along the length of the plug 18, together with its relatively close fit in the tube 6, provides a ready means for maintaining the shank 19 rigidly and accurately 55 centered in the tube 6, and hence centered in the spring 16. This effect is further enhanced after one or two firings of the gun, the recoils from which drive the cap 13 against the under side of the head 20 clamping it more securely 60 against the inner face of cap 7. The shank 19 is thus placed in such a position that it does not interfere in any manner whatsoever with the action of the spring 16. To interfere with the action of the spring 16 would be distinctly 65 disadvantageous. For example, a device which reduced the capacity of the magazine by forcing the cap 13 up farther into the tube, and thereby compressing the spring 16 initially beyond its intended compression, would be disadvantageous, in that it would tend, in the course of time, to reduce the resiliency and life 70 of the spring 16. Or, any device which would be likely to rub the spring 16 as it was compressed and expanded, such as a loose-fitting

device, would introduce an unnecessary frictional wear on the spring 16, and cause it to cease functioning before the expiration of its normal life.

The plug as described has neither of these 5 disadvantages, and in no wise interferes whatsoever with the action of the spring or the magazine.

The manner in which the plug 18 limits the capacity of the magazine tube is shown in Fig. 10 10 3, where it is seen that after two cartridges 17 have been introduced, the introduction of a third cartridge 17A is prevented by the engagement of the inner face of the cap 10 with the end of shank 19 of the plug 18. 15

If it is desired to return the magazine to its normal loading capacity, this may be accomplished with great facility merely by removing the cap 7 from the end of the tube 6, manually withdrawing the plug 18, and replacing the cap 20 7. The magazine will thereupon be capable of receiving four cartridges, as illustrated in Fig. 4.

The rigid positioning of the plug 18 in position in the magazine likewise has the distinctly desirable effect of preventing rattling. 25

It is preferable that the plug 18 be made of wood, such as hickory, and in one piece, as the lightness of wood is a distinct advantage over the corresponding heaviness of even the lighter metallic alloys. It is desirable to keep the plug 30 18 as light as possible, so that it will have no tendency to affect the balance of the gun when it is held in firing position.

So far as the adaptability of the present invention is concerned, the magazine tubes of both 35 the automatic or auto-loading shot guns and the repeater type of shot guns are of identical construction. This is not to be construed literally, but only to mean that the present invention, in substantially the same shape as that shown, may 40 be adapted with substantially equal facility to automatic, or auto-loading, and repeater type shot guns.

In view of the above, it will be seen that the several objects of the invention are achieved and 45 other advantageous results attained.

As many changes could be made in carrying out the above constructions without departing from the scope of the invention, it is intended that all matter contained in the above description or shown in the accompanying drawing shall be interpreted as illustrative and not in a limiting sense. 50

We claim:

1. The combination of a shot gun magazine 55 tube having a compression spring therein and a cap fitted into said tube and receiving the thrust of the compression spring, and a second cap threaded on to the end of the tube, with a plug having a shank extending through a central opening in said first-named cap and inside said compression spring, and being held in position at least in part between the outer face of said first-named cap and the inner face of said second- 60 named cap.

2. The combination of a shot gun magazine tube having a compression spring therein and a cap fitted into said tube and receiving the thrust of the compression spring, and a second cap 70 threaded on to the end of the tube, with a plug for reducing the capacity of said tube, said plug having a shank extending through a central opening in said first-named cap, said plug also having a head which is clamped between the 75

outer face of said first-named cap and the inner face of said second-named cap, thereby supporting said plug in rigid assembly with the magazine tube.

5 3. The combination of a shot gun magazine tube having a compression spring therein and a cap fitted into said tube and receiving the thrust of the compression spring, and a second cap threaded on to the end of the tube, with a plug 10 for reducing the capacity of said tube, said plug having a shank extending through a central opening in said first-named cap, said plug also having a head which is clamped between the outer face of said first-named cap and the inner 15 face of said second-named cap, thereby supporting said plug in rigid assembly with the magazine tube, said shank having a diameter less than the inner diameter of said compression spring, whereby it does not interfere with the 20 operation of said compression spring.

4. The combination of a shot gun magazine tube having a compression spring therein and a cap fitted into said tube and receiving the thrust of the compression spring, and a second cap 25 threaded on to the end of the tube, with a plug for reducing the capacity of said tube, said plug having a shank extending through a central opening in said first-named cap, said plug also having a head which is clamped between the outer 30 face of said first-named cap and the inner face of said second-named cap, thereby supporting

said plug in rigid assembly with the magazine tube, said shank having a diameter less than the inner diameter of said compression spring, whereby it does not interfere with the operation of said compression spring, said head having a diameter substantially equal to the inner diameter of the magazine tube, said head being of substantial thickness along the axis of the plug. 5

5. The combination of a shot gun magazine tube having a compression spring therein and a cap fitted into said tube and receiving the thrust of the compression spring, and a second cap threaded on to the end of the tube, with a plug for reducing the capacity of said tube, said plug having a shank extending through a central 10 opening in said first-named cap, said plug also having a head which is clamped between the outer face of said first-named cap and the inner 15 face of said second-named cap, thereby supporting said plug in rigid assembly with the magazine tube, said shank having a diameter less than the inner diameter of said compression spring, whereby it does not interfere with the operation of said compression spring, said head having a diameter substantially equal to the inner 20 diameter of the magazine tube, said head being of substantial thickness along the axis of the plug, said plug being made of wood.
